COMMUNICATION SYSTEM

Harry J. Nichols, Binghamton, N. Y., assignor to International Business Machines Corporation, New York, N. Y., a corporation of New York

Original application January 29, 1934, Serial No. 708,767, now Patent No. 2,104,571, dated January 4, 1938. Divided and this application April 16, 1937, Serial No. 137,204

10 Claims. (Cl. 178—4.1)

This invention relates to synchronous communication systems and particularly to single impulse printing telegraph systems, and the present application is a divisional case of the copending application, Serial No. 708,767, filed January 29, 1934, now Patent No. 2,104,571, granted Jan. 4, 1938.

The present application relates specifically to the motor control circuits and therefore has for its object to provide a novel operating method in printing telegraph systems, whereby the operator at the sending machine can initiate operation of the receiving machine, establish proper conditions of synchronism and thereafter control the printing operations of the receiving machine.

Further and other objects and advantages will be hereinafter set forth in the accompanying specification and claims, and shown in the drawings, which by way of illustration show what is now considered to be the preferred embodiment of the invention.

In the drawings:

Fig. 1 shows in diagrammatic form the circuits and apparatus which, together with the typewriter or printer typing mechanism, comprise a complete communication unit. The circuits are shown in the receiving condition, or more precisely, in readiness to receive.

Fig. 2 shows in diagrammatic form the particular parts of the circuit and apparatus used to control the key board and to prevent the transmission of false signals.

Fig. 3 is a diagram showing the arrangement of circuits, apparatus, and switches whereby automatic starting of the receiving machine is accomplished.

In the several figures, like characters represent like parts.

General description

For purposes of description and as illustrative of a preferred embodiment of the invention, a complete communication unit is hereinafter described as comprising a typewriter, a typewriter control unit, and a distributor unit. The typewriter control unit is preferably mounted underneath and inside the typewriter frame. The distributor unit is preferably housed in a case located near the typewriter. The two units are conveniently connected electrically by a multiple conductor cable.

The complete communication units may be used in pairs, one unit sending while the other receives and vice versa, or they may be connected in such a manner that the sending unit controls

a group of receiving units. Units may be connected for communication purposes by means of general communication systems, such as a telegraph, telephone, or radio system, or simply by a pair of wires, or one wire and ground.

In Fig. 1, the apparatus comprising the typewriter control unit is included within the dot-dash rectangle; all other apparatus is included in the distributor unit.

The apparatus shown in Fig. 1 performs the 10 functions of transmitting and receiving synchronizing and printing signals, and utilizing these signals, and responsive local impulses, for various starting, synchronizing, selecting, and control purposes. The local impulses are distributed to their proper circuits by the rotary distributor.

Referring now to Fig. 1 in detail, the rotary distributor 15 consists of a series of insulated metallic segments 16 and a solid metallic ring 17 mounted on a suitable disc of insulating material (not shown). A rotary contactor 18 is frictionally driven by drive motor 19 and contacts each segment once during each revolution in a well understood manner. The drive motor 19 must be of exactly uniform speed, or suitable governing means must be employed to obtain a highly uniform speed.

The rotary contactor 18 is shown in the rest position on number 2 segment. A release magnet 20, functioning as a start-stop means, is provided to stop and release rotary contactor 18 in accordance with the invention, and for illustrative purposes is shown with its armature 21 in engagement with contactor 18. Armature 21 also operates spring contacts 25 and 26 which function in connection with starting operations. Release magnet 20 is provided with a low impedance winding 22 and a high impedance winding 23 connected in series aiding relation. Across the terminals of winding 23 is connected storing condenser 24. Release magnet 20 is of the quick acting, slow release type which responds quickly to a short current pulse, but holds for a protracted period, hence if supplied with properly timed impulses, continues to hold in the operated position so long as such pulses are regularly received, but drops out shortly after the pulses cease, or in case the pulses are too greatly diminished. An improved relay or magnet of this type, which may be termed a pulse sustained relay, is described in detail in my copending patent application, Serial No. 672,161 filed May 22, 1933.

The power for transmission purposes and for the operation of the various relays and magnets

is obtained from any suitable direct current source, preferably from a rectifier assembly as shown.

The output of the rectifier is applied to the 5 terminals of a four section voltage divider 44, as shown. The positive bus 42 is connected to the positive terminal of voltage divider 44, and the negative bus 40 to the negative terminal. The zero bus 41 is connected to the zero or ground 10 terminal between sections 44a and 44b of voltage divider 44, section 44a thus furnishing in a well understood manner negative bias for the grid 133 of electronic relay 130.

The elements of electronic relay 130, which is of 15 the grid controlled, gaseous discharge type are the grid 133, the cathode 134, and the anode or plate 135, all contained in an envelope 132 containing gas or vapor at low pressure, as is well understood.

20 In series with the anode-cathode circuit of relay 130 is the cut-off relay 170, connected as shown, with winding 171 shunted by variable resistor 172 and provided with spring contacts 173 and 174. As is well known, the grid of a grid controlled gaseous discharge tube is normally unable to stop the discharge through the anode circuit when once started, and in general, either the plate current must be cut off, or else the plate must be rendered negative in respect to the cathode. It is preferred to cut off the plate current after a properly timed interval by utilizing cut-off relay 170 to open contacts 173-174. The variable resistor 172 permits of very exact timing of the cut-off interval, and the location of the relay 25 in the circuit as shown is found to give quick and reliable de-ionization of the electronic relay 130. A spark suppressor arrangement may be connected across contacts 173-174 as shown to reduce sparking to a negligible degree.

40 The non-repeat relay 140 is connected in circuit only while sending, and has for its principal function the prevention of the transmission of false signals. It will be explained in detail hereafter in connection with Fig. 2.

45 The multiple switch relay 160, controlled by send-receive switch 190, provides the automatic switching operations required to change from sending conditions to receiving conditions and vice versa. It is provided with a single winding 50 161 and five sets of contact springs numbered 1-14 inclusive. In order to simplify the diagram, these contacts are shown in their natural locations in the circuit. The winding of relay 160 is connected 55 in series with the windings of release magnet 20 across section 44d of the voltage divider reducing the voltage across these windings and economizing on holding current.

The start relay 50 is connected across the line 60 on receiving so as to respond to received signals. It is of the pulse sustained type and performs various switching operations to start the receiving machine automatically. It will be more fully described hereinafter in connection with Fig. 3.

The input transformer 32 is connected to the 65 line on receiving by start relay 50. It applies the signal pulses to the grid of electronic relay 130.

Included in the typewriter control unit is the 70 key solenoid assembly suitably mounted, consisting of a bank of solenoids 158, one for each operating key 156 of the typewriter or printer. The plunger of each solenoid is connected to its associated key lever by means of a spring link 184. This construction provides smooth operation of the printer actuating levers, and improves the pull characteristics of the solenoids.

Each key lever 156 has associated with it an individual key switch 157, of break-make type, actuated by an individual insulated push rod 155. The armature spring of each key switch is connected to an individual segment, to make springs 5 being connected to the common key-switch bus 138 as shown, while the break springs are connected to the individual solenoids. A universal bail 153 is positioned below and transversely across the row of key levers, being held in light 10 contact therewith by a retractile spring (not shown). When any key is depressed, bail 153 closes auxiliary switch 154 by means of push rod 155. Auxiliary switch 154 forms a part of the key-latch and non-repeat arrangement. 15

The key latch 151 consists of a pivoted, universal latch bar extending across the ends of all the key levers, the ends of which are provided with a square projection as shown. A retractile spring 183 attached to latch 151 so as to obtain proper 20 leverage normally holds the latch out of engagement with the key levers. The key latch magnet 150 actuates the key latch, as will be more fully explained in connection with Fig. 2. The send-receive switch 190 is a two-position switch which 25 switches certain circuits from sending to receiving conditions, as required.

Sending circuits and operations

Referring to Fig. 1, the transmission of syn- 30 chronizing signal impulses is accomplished as follows:

Assume that drive motor 18 is operating and tending to rotate rotary contactor 18 by a friction drive but that the contactor is held in the rest position on segment 2 by armature 21 of release magnet 20. To start sending synchronizing signals, send-receive switch 190 is thrown to the S or send position. This completes a circuit from positive bus 42 through winding 22 and condenser 24 of release magnet 20 via contacts 192-191 of send-receive switch 190, through winding 161 of relay 160 to the voltage divider between sections 44c and 44d. A current pulse through this circuit operates relay 160, breaking contacts 2-3, 45 5-6, 8-9, 11-12, and making contacts 1-2, 4-5, 7-8, 10-11, 13-14. Release magnet 20 is also energized, attracting armature 21 which releases rotary contactor 18. As condenser 24 becomes charged a small steady current limited mainly by the resistance of windings 23 and 161 50 flows through these windings providing sufficient holding current to hold relay 160 and magnet 20 in the operated condition. A strong operating pulse followed by low holding current is thus provided. 55

On being released by armature 21, contactor 18 is set in rotation by the friction drive and takes up the uniform speed of the motor drive shaft. When contactor 18 reaches segment 1, a circuit is completed from positive bus via contacts 8-1 through inductance 167, via contacts 4-5 to segment 1; thence via contactor 18 to ring 17 and via contacts 2-1 and 10-11 through line and return to zero bus via ground. For the duration of contact with segment 1, current flows through the circuit just traced, and a signal impulse is sent to the line. This periodic signal impulse, which is repeated for each revolution of contactor 18, constitutes the synchronizing signal. 60

Inductance 167, which is included in the circuit transmitting the synchronizing signal, is designed to match the inductance of winding 147 of non-repeat relay 140 which is included in the circuit transmitting printing signals, hence 70 75

the amplitude and wave form of the synchronizing signals and printing signals are substantially identical.

To commence sending printing signals, send-receive switch 190 is thrown to the S position, and synchronizing signals are sent to the line for a few seconds to permit the receiving machine to come to synchronism as hereinafter described. Printing signals may then be sent by depressing 10 the typing keys of the typewriter as for ordinary typing.

Referring to Fig. 2, and assuming that key A is struck, a printing signal is transmitted as follows: As the key is depressed, the middle and lower contacts of its own particular key switch are closed, thus connecting sending bus 138 to a particular segment, in this case to segment 4. When rotary contactor 18 arrives at segment 4, a circuit is completed from positive bus 42 20 through winding 147 of non-repeat relay 140 via contacts 141-142 of same, to send bus 138, via contacts of closed key switch 157 to segment 4, via contactor 18 to ring, thence via contacts 2-1 and 10-11 to line and return to zero bus via ground. A current pulse flows through this circuit including the line, its duration being determined by the time of contact of contactor 18 with the connected segment. Such aperiodic signal impulses, distinguished in respect to the time interval from the preceding synchronizing signal, 30 constitute the printing signals.

Concurrently, as the key lever nears the bottom of its stroke, the printing mechanism (not shown) of the typewriter is tripped, and the typewriter immediately types the proper character to furnish a local copy of the message.

Key latch and non-repeat arrangement

Instantly upon the depression of a printing key, the key latch arrangement is operated as follows: Each time a key is depressed, universal bail 153 closes the contacts of auxiliary switch 154 by means of push rod 155. The lower spring of the auxiliary switch is connected to ground and the upper spring is connected via contacts 194-193 to contact 145 of non-repeat relay 140. Upon closing of the auxiliary switch contacts, a circuit is completed from ground via contacts of auxiliary switch 154 and contacts 194-193 and 50 145-144 through winding 152 of latch magnet 150 to tap 44f of voltage divider 44. A current pulse through the circuit just traced operates latch magnet 150 which by means of spring link 184 and crank arm 189 quickly hooks the pivoted latch member 151 over the end of the depressed key lever, latching it down. This is done so quickly that the finger can be removed from the struck key with great rapidity without danger of premature release of the key lever.

As illustrated in Fig. 2, the latch member 151 not only serves to hold down the depressed key, but also serves as an interlock to hold all other keys against being depressed, thus guarding against depressing a second key before the printing signal from the connected segment is sent to the line. This arrangement has the advantages of not requiring additional interlocking means to obtain this feature, and also in that the interlocking feature only comes into play during sending, the key board being entirely free when receiving. As a consequence, less actuating force for the key levers is required permitting smaller key solenoids to be employed.

The printing impulse previously described, in addition to sending a printing signal to the line,

also performs an important function in the key-release and non-repeat operations. The printing impulse flowing through winding 147 energizes non-repeat relay 140, which operates, opening contacts 141-142 and 144-145, and closing 5 contacts 142-143 and 145-146. Opening contacts 141-142 disconnects winding 147 which is too low in resistance to place directly across the line. Opening contacts 144-145 cuts holding current off winding 152 of latch magnet 150 which 10 releases, thus permitting retractile spring 183 to draw latch 151 away from the key levers, thus releasing all keys insofar as the latch arrangement is concerned. It is possible, however, that a key may be inadvertently held down by the 15 finger after being released by the latch, and in this event, it is necessary to prevent false repeat signals from being sent to the line. Therefore, when contacts 145-146 are closed, send bus 138 is connected via these contacts to ground, hence 20 any connected segment, except the synchronizing segment, is placed at zero potential, and no more printing signals can be sent to the line so long as contacts 145-146 remain closed. Closing contacts 142-143 supplies holding current for 25 winding 148 through a circuit from voltage divider tap 44f through winding 148 via contacts 143-142, 146-145, 193-194 and auxiliary switch 154 to ground. When the depressed key is released, auxiliary switch 154 is opened, taking 30 holding current off the non-repeat relay, which releases and opens contacts 143-142 and 146-145. This completes the cycle, and leaves all sending circuits in normal condition.

It will be noted that the key latch 151 serves 35 as a key board lock during the brief but variable interval from the instant a key is depressed until the signal impulse is transmitted by rotary contactor 18, whereupon the non-repeat relay cuts off the current from the latch magnet. Simultaneously, the non-repeat relay grounds the send bus and hence any connected segment, preventing further signals being sent to the line until all keys are released. The result is that only one signal can be sent for each cycle of operation of 40 a key lever. This constitutes the non-repeat feature. In case continued repeat signals from a key are desired, it is only necessary to connect the key latch switch of that particular key to positive bus instead of to the send bus, which 45 exempts that particular key from the non-repeat feature.

In normal operation, the keys are depressed and released quickly, and the key board is released for further writing practically instantly 50 when the signal is sent to the line.

Starting circuits and operations

Referring to Figs. 1 and 3, and more particularly to Fig. 3, the apparatus primarily involved in receiving both synchronizing and printing signals comprises start relay 50, the primary winding 33 of input transformer 32, and their associated circuits and switches. Start relay 50, preferably of the pulse sustained type previously described, is preferably provided with a low impedance operating winding 56 and a high impedance holding winding 57 wound on the same core and connected in series aiding relation. Across winding 57 is connected storing condenser 60 58. The impedance of the windings and condenser in combination should preferably match the impedance of the transmission line or connecting transmission circuits. As compared to release magnet 20, start relay 50 need not be as 65 70 75

- powerful, since it is required only to operate its own contact springs, and need not respond to the first pulse received. Likewise, it is not essential that start relay 50 have separate operating and holding windings, although there is in some cases an advantage in having a separate operating winding, both in respect to a more prompt response and in compensating for primary winding 33, as more fully explained hereinafter.
- 10 Relay 50 is provided with a pair of make contacts 51-52, and a set of break-make contacts numbered 53-55 inclusive. In parallel with make contacts 51-52 are connected make contacts 13-14 which may be actuated either by multiple switch relay 160 as indicated above, or manually by send-receive switch 190, as may be preferred. Contacts 13-14 function in the starting of drive motor 19 when initiating sending conditions.

The operation of the automatic start arrangement is as follows: The incoming signals, assumed to be the synchronizing signals, are received at the line terminals 30, 31 and traverse the circuit from terminal 30 via contacts 11-12 via contacts 54-55 through winding 66 and condenser 58 to terminal 31. The pulses through this circuit build up the charge on condenser 58 faster than the charge leaks off through winding 57, thus energizing relay 50 which pulls in its armature on a signal pulse, opening contacts 55-54, and closing contacts 54-53, and 52-51. Opening contacts 55-54 removes the short circuit on primary 33, which thus becomes capable of functioning. Closing contacts 54-53 short circuits winding 56, whose impedance is thus removed from the signalling circuit to compensate for the addition of the impedance of winding 33. Closing contacts 52-51 connects power to drive motor 19 and, if required, to the typewriter motor in instances where electric driven typing machines are employed. It is to be noted (Fig. 3) that a two-way manual switch SW is provided for the typewriter motor, so that this motor may be started automatically if not already running.

So long as signals are regularly received, relay 45 50 remains operated; if signalling is discontinued, or interrupted, the charge on condenser 58 is not replenished, and relay 50 releases, restoring all circuits to initial conditions. This completes the cycle of operations of the automatic start arrangement, which provides means for starting up the receiving machine in the absence of attendants, after which messages may be received in the usual manner. It also provides for shutting down the receiving machine during idle 55 periods.

It is to be noted that the arrangement illustrated assumes that power is already turned on the rectifier apparatus and also on the cathode of the electronic relay 130. This is the preferred 60 arrangement where messages are being sent back and forth frequently, since there is no need to wait until the rectifier and electronic relay tubes are warmed up before starting transmission. Where messages are sent infrequently, or the 65 warm up period is negligible, or the saving by not having the tubes lighted is a consideration, start relay 50 can be utilized to turn current on the rectifier, or electronic relay, or both, as desired. Such variations in switching arrangements to meet various operating conditions will be evident to those skilled in the art and are clearly within the scope of the invention.

Synchronization

75 The operations connected with the sending of

the periodic synchronizing signals have already been described. Referring again to Fig. 1, the operations connected with receiving and utilizing these signals are as follows: The first step is that of establishing synchronism of rotary contactor 18 of the receiving machine with the received synchronizing signals. Since the periodic synchronizing signals are sent from a particular segment, termed the synchronizing segment, of the sending machine, it follows that for complete 10 synchronization, the rotary contactor at the receiving machine must arrive at the leading edge of the synchronizing segment each time a synchronizing signal arrives from the sending machine.

At the receiving station, the synchronizing signals are received at the line terminals 30 and 31, and upon the operation of start relay 50 are applied to the primary 33 of input transformer 32. Concurrently, the drive motor is started up, 20 as previously described. The synchronizing signals through primary 33 induce a voltage across secondary 34 and shunt resistor 35, and with proper polarity, alter the bias voltage on grid 133 and trigger off electronic relay 130, which 25 becomes ionized and conducting, thus permitting a strong current flow in its plate circuit. The contactor 18 being held at rest on segment 2, a circuit is completed from zero bus via contacts 173-174, through relay winding 171 via center 30 tap 136 of power transformer 137 to cathode of relay 130 thence to plate 135, via contacts 3-2 to ring, via contactor 18 to segment 2, via contacts 26-25 through condenser 24 and winding 22 to positive bus. A strong current pulse flows through 35 this circuit, operating release magnet 20 and thereafter cut-off relay 170, which opens contacts 173-174, terminating the pulse. The armature 21 is quickly pulled in, releasing contactor 18 and opening contacts 25-26. The pulse of current through condenser 24 charges that condenser, providing holding current for relay 20, and preventing the release of armature 21.

Upon release, contactor 18 is set quickly in motion by its friction drive, and is thereafter rotated 45 at uniform speed by drive motor 19. Contactor 18, having been released from segment 2 in response to a pulse occurring concurrently with the passage of the contactor across segment 1 at the sending station would arrive at segment 1 before 50 the arrival of the next synchronizing signal, were it not for a slight delay in the operation of relay 20 and a slight amount of slip of the friction drive. Because of these delays, the lead provided by starting contactor 18 from segment 2 enables the contactor to arrive at the leading edge of segment 1 as the next synchronizing signal is received. This synchronizing signal energizes electronic relay 130 as before, but this time the local circuit is completed via segment 1, the circuit of 55 segment 2 having been opened at contacts 25-26 by the operation of release magnet 20. The current pulse through the completed circuit replenishes the charge on condenser 24, maintaining release magnet 20 in the operated position, hence 60 armature 21 does not interfere with contactor 18 which continues in rotation so long as it arrives on segment 1 in unison with the synchronizing signal. Means are provided for adjustment of the starting position of contactor 18, and also of 65 the frictional driving force, thus enabling exact timing of the starting revolution to be made. In practice, it is found that with proper adjustments, synchronism is accurately established on the first revolution. Thereafter, the mainte- 70 75

nance of synchronism depends on the preservation of precisely uniform speed of the drive motors at the sending and receiving machines. Should, for any reason, unison within approximately one-half segment width be departed from, or the incoming synchronizing signals be interrupted beyond a predetermined interval, contactor 18 is stopped on the rest segment by reason of release magnet 20 dropping out through lack of sufficient holding current. The synchronizing procedure is then repeated when the next synchronizing pulse is received. Thus synchronism, if lost, is automatically re-established.

The system of synchronizing herein described is particularly adapted to communication systems to be operated in regions having a common power system of accurately controlled frequency, in which circumstances good results are obtained from synchronous drive motors supplied with power from the common system. As is well understood, the employment of synchronous motors in such installations assures virtually perfect isochronism, and if the receiving machine is established in the proper phase relation, synchronism with the sending machine will continue practically indefinitely. For installations where suitable synchronous power is not available, the synchronizing system disclosed in my copending application Serial No. 672,161 filed May 22, 1933 may be preferred.

Receiving circuits and operations

Synchronism having been established as previously described and the rotary contactors at the receiving and sending stations being in unison, printing signals may be sent to the receiving station as described in connection with sending operations.

Referring to Fig. 1, the printing signals when received are applied to primary 33 as previously described, and potential variations from secondary 34 trigger off electronic relay 130 which becomes conducting. A circuit is thus completed from zero bus via contacts 173-174, through relay winding 171 via center tap 136 of power transformer 137 to cathode of relay 130, thence to plate 135, via contacts 3-2 to ring as before described, and thence via contactor 18 to the segment with which it is in contact. The response of electronic relay 130 to signals being practically instantaneous, and contactor 18 being in unison with the corresponding member at the sending station, it is evident that the contacted receiving segment will correspond to the sending segment. From this segment, of which segment 4 may be considered an example, the circuit continues via the middle and upper contacts of key switch 157 through winding 159 of key magnet 158 to key magnet bus 139 via contacts 9-8 to positive bus. The pulse through this circuit energizes key magnet 158 whose plunger is attracted, stretching spring link 184 which pulls down the key lever to which it is attached. The key lever trips the typewriter or printer mechanism (not shown) printing the selected character. As the key lever nears the end of its downward travel, push rod 155 opens the key switch contacts. Owing, however, to inertia of the key lever and other retarding effects, the circuit is actually broken by the opening of contacts 173-174 by cut-off relay 170 which is preferably adjusted to cut off the current just short of the termination of the line signal. With perfect unison, the circuit is broken before contactor 18 leaves the connected segment.

75 While there has been shown and described and

pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a motor remote control system, controlling means producing periodic impulses, transmission means for said impulses, a motor, and relay switching means for applying power to said motor comprising a relay responsive to said impulses and electrical storing means cooperating with said relay to sustain the operation of the relay during the interval between impulses.

2. In apparatus of the character described, a sending station, a receiving station, means at said sending station for sending single periodic impulses of definite periodicity, relay means at said receiving station responsive to said periodic impulses to condition the receiving apparatus for reception of printing signals, means operable for a predetermined period greater than the period of said impulses for retaining said relay in operative condition during the sending of said impulses and providing for the release of said relay upon interruption of said series of impulses.

3. A system of the character described comprising, in combination, means to transmit periodic control impulses, means to receive said impulses including control relay means, a normally inoperative motor associated with said receiving means, said relay means energized and rendered operative by the said impulses to render the said motor operative, and means cooperating with the relay means to maintain the relay means operative during the interval between the arrival of successive impulses.

4. A system of the character described comprising, in combination, means to transmit periodic control impulses, means to receive said impulses, a normally inoperative motor, means controlled by the receiving means and operated upon receipt of said impulses to render the motor operative, and means cooperating with the said controlled means to maintain the control means operative during the interval between the arrival of successive impulses.

5. A system of the character described comprising, in combination, means to transmit aperiodic character impulses and periodic control impulses, means to receive the said impulses including means adapted to be responsive to and controlled by the character impulses, a normally inoperative motor, means controlled upon receipt of the control impulses to render the motor operative, and means associated with the last mentioned means to control the character impulse responsive means upon operation thereof so as to be responsive to the character impulses.

6. A system of the character described comprising, in combination, means to transmit aperiodic character impulses and periodic control impulses including a plurality of impulse initiating circuits conditioned in succession to transmit the impulses, means to receive said impulses and including a plurality of normally inoperative impulse receiving circuits adapted to be responsive to said impulses, means responsive to the periodic impulses and operated upon receipt thereof, the operation of said means rendering the plurality of impulse receiving circuits operative so as to

be responsive to the character impulses and means to render said means, which is operated by the periodic impulses, operative during the interval between the arrival of successive impulses.

7. A system of the character described comprising, in combination, means to transmit aperiodic and periodic control impulses, means to receive said impulses including normally inoperative rotary means, a plurality of circuits, means responsive to and operated by the periodic control impulses upon receipt thereof to render said rotary means operative thereby rendering the plurality of circuits responsive to the aperiodic control impulses, and means to maintain the rotary means operative during the interval between the arrival of successive impulses.

8. A system of the character described comprising, in combination, means to transmit aperiodic and periodic control impulses, means to receive said impulses including a circuit including control means responsive to the periodic impulses, and operated thereby, a normally inoperative motor rendered operative upon operation of the said control means, means to maintain said motor operative during the interval between the arrival of successive impulses, the operation of said control means rendering the circuit respon-

sive to and controlled by the aperiodic control impulses.

9. A system of the character described comprising, in combination, a plurality of typewriters, each having means for sending or responding to aperiodic and periodic control impulses, including a motor, and means for placing one typewriter in condition to operate the motor and send out the said impulses and means for putting the other typewriter in condition to respond to the impulses thereby rendering the motor operative upon receipt of the periodic impulses.

10. A system of the character described comprising, in combination, a plurality of typewriters, each having means for sending or responding to aperiodic and periodic control impulses, including a motor, and means for putting one typewriter in condition to operate the motor and send out the said impulses, means for putting the other typewriter in condition to respond to the impulses thereby rendering the motor operative upon receipt of the periodic impulses and means rendered responsive to the periodic impulses to maintain the motor operative during the interval between the arrival of successive impulses.

HARRY J. NICHOLS.
